UNITED STATES PATENT OFFICE.

CHARLES A. LE DUC, OF LOWELL, MASSACHUSETTS, ASSIGNOR OF THIRTY-FIVE ONE-HUNDREDTHS TO HARRY SNIDER, OF LOWELL, MASSACHUSETTS.

DIE.

1,182,493.

Specification of Letters Patent.

Patented May 9, 1916.

Application filed November 11, 1915. Serial No. 60,923.

To all whom it may concern:

Be it known that I, CHARLES A. LE DUC, a citizen of the United States, residing at Lowell, in the county of Middlesex and 5 State of Massachusetts, have invented certain new and useful Improvements in Dies, of which the following is a specification.

This invention relates to dies especially of the reversible type which are used for 10 cutting blanks from thin sheet material such as upper leather for boots and shoes. It is especially adapted for skeleton double edged or reversible dies which can be operated from either side to cut rights or 15 lefts. The top and bottom cutting edges of such dies are usually of the same form, one of said edges being used for rights and the other for lefts, the die being reversible.

One purpose of my device is to provide a 20 frame and a holder for the die and a protector for the cutting edge which is from time to time at the top whereby such dies may be used in the well known forms of clicking presses. Such frame is so made 25 that it can be shifted so as to protect the other edge when the die is reversed.

Another purpose of my invention is to so 30 arrange counter operating mechanism that the total number of blanks cut or preferably the number of rights and also the number of lefts will be automatically registered by the press buffer engaging the die.

In the drawings, Figure 1 is a plan view 35 of one form of die, suitable for cutting out the tongues of shoes, equipped with my device. Fig. 2 is a sectional elevation looking upward on the line X—Y of Fig. 1. Fig. 3 is a sectional elevation on the line S—T of Fig. 1. Fig. 4 is a plan view of 40 another form of die such as is suitable for cutting out the uppers for shoes. Fig. 5 is a detail showing a modified form of bearing slot. Fig. 6 is a plan view showing an exterior frame instead of an interior frame. Fig. 7 is an elevation with parts broken 45 away showing my device arranged with counter operating means. Fig. 8 is a detail in elevation of one form of registering mechanism. Fig. 9 is a detail plan view 50 thereof. Fig. 10 is a detail in elevation showing a modification of the counting mechanism.

A represents a reversible die having top cutting edges 10 and bottom cutting edges

11 of any usual form. It is shown as a 55 skeleton frame and to the inside faces 12, I attach a plurality of bearing pins 20, 21 in such position as to project at substantially right angles to and midway between the cutting edges. 60

The protecting frame is shown as comprising side bars or members 32 and 33 from which extend brackets 34 detachably fastened together by means of bolts 35 and nuts 36. Extending through the side members 32 and 33 of the frame are a plurality of openings or slots 31 such as shown in Fig. 3 through each of which passes a pin 20 or 21. Each slot has a top shoulder such as 37 and a bottom shoulder such as 38, 70 either of which is engageable with a pin and against either of which a pin can bear. The top and bottom of the pins, the faces of the shoulders and the top and bottom faces of the frame are preferably all parallel with each other and with the top and bottom cutting edges of the die. The depth of the frame is such that its top face will project beyond the top cutting edge of the die and its bottom face will be inside the 80 bottom cutting edge thereof when the bottom shoulders rest upon the pins, that is when the pins engage the shoulders and its bottom face will project beyond the bottom cutting edge of the die and its top face will 85 be inside the top cutting edge thereof when the pins engage the top shoulders.

Referring especially to Fig. 3, it will be seen that by moving the frame up and to the left until the pins engage the bottom 90 shoulder, the frame will project beyond and protect die edge 10 and by moving it down and to the right as shown by the dotted lines, its bottom face will project beyond and protect die edge 11. The die can therefore be instantly reversed and by a quick movement of the hands the protecting frame can be brought above the top cutting edge 95 to protect it from the buffer of the press.

In Fig. 4, I show a die M of a different 100 shape which is quite irregular. In this case, the side members 40 and 41 of the frame are not parallel but are connected by a spider P as shown. In shifting this die from right to left and the frame on pins 42 105 and 43, the position of the side members with reference to proximity to die M will change as shown by the dotted lines for the

reason that these members are not parallel. The supporting pins should be long enough to prevent the frame from slipping off.

As shown in Fig. 3, the bearing slots 31 are somewhat in the form of a letter Z having a recess at the upper left to form shoulder 37 and at the lower right to form shoulder 38. Instead of this form, I may cut them as shown at 50 in Fig. 5 wherein the recesses are both at the left whereby shoulder 51 is directly over shoulder 52.

As shown in Fig. 6, I may use for a double edged die 60 an exterior supporting frame 61 from the inside of which project bearing pins 62 and 63 into engagement with slots such as 64 in the die 60. These slots are of any form desired each having a top and a bottom shoulder.

For convenience in counting the number 20 of blanks cut, I may also attach to the frame, registering mechanism, such as shown in Figs. 8 and 9, operative by push buttons 70 and 71 which project slightly beyond each face of my frame. The registering mechanism or mechanisms must be so attached to the frame that one push button will project above whichever face of the frame is at the top but the other while projecting below the bottom face of the frame, will be inside 30 the bottom cutting face of the die. Each push button, as 70, may, as shown in Fig. 8, terminate in a pawl or spring tooth 72 or 73 which engages and operates a ratchet 80 carried by a shaft 81 which also carries a bevel gear 82 in mesh with the larger bevel gear 83 which may have numbers marked upon its outer face. The relation between the teeth on the ratchet wheel and the numbers may be such that each movement of the 40 pawl will register one. I prefer to attach each counter to a bolt such as 35 by means of a frame 100 and set screw 101. This frame is formed with bracket arms 84 and 85 which carry the bearings for shaft 81 and gear 83. 45 Another arm 86 carries a pointer 87 to indicate the number registered. I may use two of such counting devices each of which is operated by a separate push button 70 and 71, in which case one will register rights and 50 the other lefts, or, as shown in Fig. 10, I may use a single counter having a ratchet wheel 80 turnable by either of two push buttons, 90 or 91. In this arrangement, one button 90 projects above the top of the 55 frame and the other 91 projects below the bottom of the frame and each carries a pawl or spring tooth as 92 or 93, both of which pawls engage ratchet 80. With this device, the total of rights and lefts is registered but 60 not the number of each. A compression spring such as 88 should be used in connection with each push button to bring it back to its normal position.

My frame may be so formed as to fit any 65 shape of die. With a die like that shown

in Figs. 1, 2, 3 and 6, which cuts the same form either side up, there is no need of reversing until one side is dulled. With such a die, only one register such as shown in Figs. 8 and 9 is necessary. When one edge dulls and the other is to be used, the register can be removed and reattached to the other side of the frame. Used in such manner, the die is substantially a single edged die and I believe that I am the first 75 to associate with a bodily movable cutting die, a push button which projects above the top thereof and which operates registering mechanism each time it is depressed by any platen or buffer, such as that of a clicking 80 press, which engages the top of the die.

Other forms of protecting frames besides those shown may be used with a double edged die and other means for shifting the frame to protect the top or bottom cutting 85 edge besides the bearing pins and slots may be used.

I claim:

1. The combination with a die having top and bottom cutting edges and a plurality of pins which project at substantially right angles therebetween, of a frame having slots each of which is in engagement with a pin and each of which has a top and a bottom shoulder either of which is engageable with 90 a pin, said frame being of such depth that its top face projects beyond the top cutting edge of the die and its bottom face is inside the bottom cutting edge thereof when the pins engage the bottom shoulders, and its bottom face projects beyond the bottom cutting edge of the die and its top face is inside the top cutting edge thereof when the pins engage the top shoulders.

2. The combination with a die having top and bottom cutting edges and a plurality of pins which project at substantially right angles therebetween, of a frame having slots each of which is in engagement with a pin and each of which has a top and a bottom shoulder either of which is engageable with 95 a pin, said frame being of such depth that its top face projects beyond the top cutting edge of the die and its bottom face is inside the bottom cutting edge thereof when the pins engage the bottom shoulders, and its bottom face projects beyond the bottom cutting edge of the die and its top face is inside the top cutting edge thereof when the pins engage the top shoulders, and push buttons 100 which project beyond the top and bottom faces of the frame, together with registering mechanism carried by the frame and operative by the push buttons.

3. The combination with a die having top and bottom cutting edges and a plurality of pins which project at substantially right angles therebetween, of a frame having slots each of which is in engagement with a pin and each of which has a top and a bottom 115 120 125 130

shoulder either of which is engageable with a pin, said frame being of such depth that its top face projects beyond the top cutting edge of the die and its bottom face is inside the bottom cutting edge thereof when the pins engage the bottom shoulders, and its bottom face projects beyond the bottom cutting edge of the die and its top face is inside the top cutting edge thereof when the pins engage the top shoulders, and two push buttons which project beyond the top and bottom faces of the frame, the bottom one being inside the bottom cutting edge of the die, together with registering mechanism carried by the frame and operative by the push buttons.

4. The combination with a cutting die operable by the engagement of its top edge with a platen, of a push button which projects above said top edge, and registering mechanism operated by said push button. 20

5. The combination with a die having top and bottom cutting edges, of a frame so attached thereto as to be shiftable without removing it therefrom to project beyond and 25 protect the top edge thereof when the die is in use in a clicking press and to leave the bottom edge exposed.

In testimony whereof I hereto affix my signature.

CHARLES A. LE DUC.
